UNITED STATES PATENT OFFICE.

SIMON SNYDER, OF MUNCY, PENNSYLVANIA, ASSIGNOR TO SPROUT, WALDRON & CO., OF MUNCY, PENNSYLVANIA, A CORPORATION OF PENNSYLVANIA.

FEEDING AND MIXING MACHINE CONNECTED IN GANGS.

Application filed April 7, 1926. Serial No. 100,427.

This invention relates to feeding and mixing machines of the kind used in flour mills for feeding and mixing granular material or different kinds of grain, either whole or 5 granulated, and various kinds of stock feed, such as oats, middlings, or ground alfalfa, and more particularly to machines of the character shown and described in my Patent No. 1,530,143, granted March 17, 1925, 10 adapted to be connected in gangs for feeding and mixing different kinds of grain or granulated material in measured or predetermined quantities; a group of such machines being connected with a mixing device common to the entire group, whereby 15 different kinds of materials delivered by different machines in the group may be mixed, in either the same or different proportions, as desired, all in a continuous operation.

One object of my present invention is to simplify and improve the construction and increase the efficiency of machines of the character shown in my aforesaid patent.

Another object is to provide a feeding machine of the character referred to consisting of few parts assembled in compact form and less expensive to make and less liable to get out of order than the more complex machines of the character referred to as heretofore constructed.

Another object is to provide simple and efficient means connected with the discharge port of each machine in a group for conducting the material therefrom into a receptacle or conveyor trough common to the entire group and which may be shifted to effect a discharge into a receptacle at one side of the individual machine for the purpose of ascertaining whether such machine is feeding in the desired proportion.

Other objects will more fully appear from the following description.

The invention will first be hereinafter 45 more particularly described, with reference to the accompanying drawings, which are to be taken as a part of this specification, and then pointed out in the claims at the end of the description.

In said drawings, Fig. 1 is a transverse 50 sectional view of a machine embodying my

invention, the section being taken on the line 1—1 of Fig. 2;

Fig. 2 is a front elevation of the machine partly broken away to show the interior construction;

Fig. 3 is a plan view omitting the hinged cover for the opening in the front portion of the casing so as to expose the conveyor arms of the feed wheel therein;

Fig. 4 is a vertical sectional view taken on the line 4—4 of Fig. 3;

Fig. 5 is a front elevation of a group of feeding machines operably connected with a mixing device including a spiral conveyor 65 for mixing and discharging the material fed by the group of machines into a suitable receiver; and

Fig. 6 is a detached view in side elevation of a deflecting chute whereby material issuing from the discharge port may be caused to pass either inwardly into a mixing device 70 or outwardly into a separate receptacle.

Referring to said drawings, in which the same reference characters are used to denote 75 corresponding parts in different views, the feeding machine shown in Figs. 1 to 4 of the drawings is designed and adapted to be used either singly or collectively as one of a group of machines for delivering grain or 80 granular material and various other food products in predetermined proportions for admixture in a suitable mixing device, while in Fig. 5 is shown a group of such feeding machines operably connected for discharging 85 their contents simultaneously into a suitable conveyor trough common to the entire group of machines and containing a rotary conveyor or other suitable device for commingling and conveying the mixture to a 90 point at which the desired commingling has been effected and then discharging the mixture into a suitable receptacle therefor.

The supporting frame 1 has a top plate 1^a of circular form having an annular shoulder 95 1^b on which is seated the lower cylindrical portion 2 of a combined feed hopper and gear casing within which the driving mechanism is housed; said gear casing also serving as a chamber beside the feed hopper 100 for delivering material to means for discharging the material into a suitable recep-

tacle or into a conveyor trough, as desired. Said casing consists of a front portion 3, a rear portion 4 and an intermediate partition 5; said front part serving as a delivery chamber and housing for the driving mechanism and having a substantially semi-circular base portion 3^a and a rearwardly inclined upper portion 3^b in which there is an opening provided with a hinged cover 3^c to permit access to the mechanism housed therein. The rear portion 4 is of approximately U-shaped form with square corners and diminishes in size toward its lower end which terminates in substantially semi-circular form concentric with a centrally disposed semi-circular part of said partition, the latter having a centrally disposed substantially semi-circular portion 5^a spaced from the rear inner wall of said rear part so that these two parts form a feed hopper having a lower end portion of arc-shaped or substantially semi-circular form overlying the feed wheel conveyor arms which, for the time being, are exposed within the hopper at the feed or delivery end thereof. Said front and rear portions 3 and 4 of the casing are formed or provided on the adjacent edges thereof with vertically disposed flanges 34 and 4^c, respectively, which are suitably apertured to receive fastening bolts 5^c having nuts screwed thereon for securing the two parts together, and also securing thereto opposite ends of the partition 5 which are fitted between said flanges. The upper part of the partition is inclined toward the front portion of the casing to widen the mouth of the hopper and has its upper edge flush with and arranged to abut against the meeting edge of the front part 3, as shown, so as to form therewith a closed top above the upper end of a vertical shaft 6 on which is secured a feed wheel 7; said shaft having fixed thereon a beveled gear wheel 8, the teeth of which engage a beveled pinion 9 fixed on a horizontal shaft 10 through which rotary motion is imparted to the feed wheel. Suitable bearings for said vertical shaft 6 are provided by means of transverse bars 11 bolted or otherwise secured to the partition 5 at the terminal points of the semi-circular portion thereof; said bars having intermediate their ends concave portions confronting similar concave parts of co-operating bearing members 11^a which are detachably secured to said bars to permit the shaft to be removed for a purpose hereinafter stated. Bearing sleeves or bushings 12 are fitted on the shaft 6 between the concave portions of the bearing members 11 and 11^a, as shown more clearly in Fig. 4, to take up wear, and the bearing caps 11^a are provided with alemite or grease cups 13 for oiling the bearings. The shaft 6 is supported on a collar 6^a secured thereon by a set screw and any end-thrust of the shaft upwardly incident to the engagement

of the pinion 9 with the gear wheel 8 is taken up by an anti-friction bearing 14 of a well known type, consisting of grooved rings placed on the shaft between the gear wheel 8 and the upper bearing members 11 and 11^a and a series of balls between the rings.

As will be observed, the feed wheel overlies the top plate 1^a of the supporting frame, which plate forms the hopper bottom, and between said feed wheel and bottom is placed an oscillatory segmental or circular plate 15, adapted to rest upon the hopper bottom and having formed therein adjacent the inner wall of the casing member 3, in front of the feed wheel shaft, an oblong arcuate slot or opening adapted to register with a similar opening in the hopper bottom through which the grain or granular material is discharged into a spout 16 which empties into a mixing device; a swinging chute being preferably interposed between the discharge port and said device, as shown in Fig. 4, for conducting the material inwardly into said spout or outwardly into a suitable receptacle, when it is desired to measure or weigh the grain to ascertain whether or not a particular machine or different machines in a group is or are discharging in the desired proportions. The oscillating plate of the feed regulating device has a centrally disposed aperture therein registering with an aperture in the top plate of the supporting frame forming the hopper bottom through which protrudes a boss the head of which is riveted or bolted to said plate and on which is secured underneath said bottom the hub portion of a segment gear 17 which engages a worm 18 on a rod 19 so that by rotating said rod 19 in a forward or backward direction oscillatory movement may be imparted to said segment or circular plate of the feed regulating device to increase or decrease the size of the feed opening in the bottom of the casing and thereby increase or decrease the amount of grain or granular material that may be discharged by the feed wheel in a given period of time. The rod 19 is revolvably mounted on a bracket 20 which is bolted or otherwise secured underneath the bottom of the casing or to the machine frame at one side thereof as shown in Figs. 1 and 2. The rod 19 has its inner end fitted in a suitable bearing therefor on the underside of the casing or hopper bottom, as indicated in dotted lines in Fig. 1, and it may be rotated by means of a hand wheel 21 fixed on its free end. It also carries or has formed thereon a worm gear 22 which engages the teeth of a gear wheel carried by or integral with a stub shaft or arbor 23 revolvably mounted on the bracket 20 as shown; said stub shaft also carrying a pointer or indicating device 24 arranged to travel around a

- graduated disk or dial 25 so that as the rod 19 is rotated for the purpose of adjusting the feed regulating device the pointer 24 will be moved so as to indicate the variations in the size of the feed opening or the amount of material that may pass therethrough in a given period of time. The feed wheel is preferably formed or provided with a centrally disposed hub portion fixed 10 on the shaft 6 and integral outwardly projecting conveyor arms or blades 27 which extend from said hub portion outwardly on a gradual curve or arc of a circle into close proximity to the cylindrical lower part of 15 the casing so as to adapt said conveyor arms or blades to "gather" the grain or granular material and push it forward so that it may not be thrown outwardly against the inner cylindric wall of the casing. But other 20 forms may be employed, for instance, conveyor arms which extend radially from the hub portion of the wheel to an intermediate point from which point they are forwardly inclined in the direction of rotation at an 25 obtuse angle to the base portion thereof, as shown in my aforesaid Patent No. 1,530,143, so as to adapt them to push the material toward the discharge port, as in the present case.
- 30 For the purpose of stirring or agitating the grain or granular material within the feed hopper so as to prevent clogging, I provide an agitating device consisting preferably of rotary blades 28 spaced apart on 35 a shaft 29, one at each side of the center of the feed wheel, and projecting from the shaft in opposite directions; said shaft being journaled in suitable bearings formed on or secured to the outer side walls of the hopper 40 section of the casing and said arms having tubular hub-like portions fitted on the shaft and secured in relatively fixed positions thereon by means of set screws so that they may be adjusted along the shaft and secured 45 in any desired position. Motion may be imparted to the agitators by sprocket-gear and drive-chain connection between the agitator shaft and the horizontal driving shaft 10, as shown in Fig. 3.
- 50 The machine may be driven from any suitable source of power by belt or other connection with a driving wheel or loose pulley 30 on the driving shaft 10; said pulley having a clutch member 31 at one 55 side adapted to engage a clutch member 32 slidably but non-rotatably secured on a projecting end of the shaft 10 so that when the two clutch members are engaged the pulley and shaft will rotate together and 60 impart rotary movement to the feed wheel, but when disengaged will allow the pulley to rotate freely on the shaft. The two clutch members are held normally in separated relation by means of a spring 33 (Fig. 2) 65 which tends to force the clutch member car-
- ried by the loose pulley out of engagement with the other clutch member, and to enable the operator to engage and disengage the clutch members at will; a lever 34 beside the pulley 30 having a hub-like portion or 70 collar 35 loose on the shaft 10 carries a wedge-shaped lug or projection 36 integral with said collar adapted to engage with cam-like action a V-shaped recess in a fixture or boss 37 projecting from the casing 75 so that when the lever is moved the pulley will be moved sidewise, causing the clutch member 31 to engage the clutch member 33 and thereby cause the pulley to rotate with the shaft. Access to the feed wheel and 80 driving mechanism housed in the casing is afforded through the opening in the front plate 3 of the casing, which is preferably of semi-circular form and provided with a hinged cover of similar form adapted to 85 be raised and thrown back so as to rest on the casing out of the way to afford access to parts within the casing for oiling or cleaning the driving mechanism and to permit the feed wheel and associated parts to 90 be removed for renewal or repairs or the substitution of a feed wheel having pockets of greater or less capacity than the feed wheel in use at the time so that the machine 95 may feed material in greater or less quantity when desired.
- It will be observed that the rear and side walls of the feed hopper section 4 converge toward the hopper bottom where they merge in the semi-cylindrical portion which partly 100 encircles the feed wheel while the partition 5 slants inwardly to a point below the mouth of the hopper and from the latter point extends in semi-circular form into close proximity to the feed wheel at the base of 105 the conveyor arms coincident with and directly over the outer edge of the imperforate centrally disposed portion of the feed wheel and forms an inner perpendicular wall of 110 the hopper, so that the material in the hopper will fall by gravity into and completely fill the pockets formed between adjacent conveyor arms, and as the feed wheel continues to revolve said conveyor arms will 115 pass underneath the lower edge of the partition 5, to which is secured a vertically adjustable valve-plate or cut-off 38 for leveling off the material in each pocket as the feed wheel revolves, so as to insure the discharge 120 of a given or measured amount of material through the feed opening within the discharge chamber by each pocket at each rotation of the feed wheel.
- The individual feeders may be driven by means of belt and pulley connection with 125 an overhead shaft, but in a group of machines the feed-wheel driving shaft of each machine is or may be driven from a main driving shaft 39 by means of sprocket wheels and chains connecting said main 130

driving shaft with each machine in the group, as shown in Fig. 5 of the drawings. To this end each machine has secured thereto at one side thereof suitable bearings for said main driving shaft, such bearings comprising a bracket bearing member 40 secured to the rear side wall of the hopper section of the casing and having secured thereto a detachable member or cap-plate 41, said bearing member and cap-plate each having a concave or substantially semi-circular recess therein to provide suitable bearings for the main driving shaft.

In order to conduct the material to be mixed either inwardly from the discharge port through the spout 16 or other conduit into the mixing device or outwardly into a separate receptacle at one side of the machine, when it is desired to measure or weigh the material to ascertain whether the machine is discharging in the desired proportion, I employ a deflecting chute which, as shown, consists of opposed metal plates 42 each having marginal flanges 43 turned toward the other plate and each secured at its upper end to a rod 44 revolvably secured on the supporting frame; one of said rods having secured thereto a weighted lever 45 adapted to hold the rod stationary in either of two positions with the chute members inclined either inwardly or outwardly as desired. The free ends of pendant arms on said rods 44 are pivoted to a link 46 whereby the two members of the chute may be thrown simultaneously into either an outwardly or inwardly inclined position when said lever 45 is thrown forward or back and retained thereby in the desired position for discharging the material delivered by the feed wheel in an inward or outward direction, for the purpose stated. The pendant arm on the innermost rod 44 to which the link 46 is pivoted has pivoted thereto a second link 47 the other end of which is pivoted to an upstanding arm 48 on a rod 49 which is revolvably supported in aligned boxes or bearings therefor secured on the supporting frames of the individual machines in the group so that when the lever 45 is actuated to throw the chute members into an outwardly inclined position, or vice versa, the chute members of each machine in the group will be simultaneously thrown outwardly or inwardly, according to the direction in which the lever 45 is moved.

The material discharged by the group of machines in the desired proportions is spouted or conducted into a subjacent mixing device, which, in the form shown, comprises a trough-like receptacle 50 within which is placed a spiral conveyor 51 on the shaft of which is a pulley 52 for imparting rotary movement thereto by connection in any well known manner with any suitable source of power. Said conveyor may be of

the form shown, or of any suitable construction, and may be operated by belt and pulley connection or otherwise with a driving shaft. The materials entering said conveyor trough are thoroughly commingled 70 therein and conveyed to a suitable receptacle therefor located at the delivery end of the conveyor or at any other convenient point underneath or below a suitable discharge spout (not shown). 75

The amount of material each machine may deliver to the mixing device in a given period of time may be varied without changing the proportions in which the material is being delivered by the individual machines, by 80 means of a cone pulley 53 on the main driving shaft having a belt or similar driving connection with a countershaft so that the driving connection may be shifted from a larger to a smaller pulley or vice versa, 85 thereby causing the group of machines to feed more or less rapidly as desired.

The operation of the machine will be readily understood from the foregoing description taken in connection with the accompanying drawings. Any desired number of feeders may be connected and operated simultaneously by the same driving shaft: four of such machines being shown in Fig. 5. At the start the feed regulating devices 90 of the individual machines are set to deliver a certain quantity of material in the desired proportions and the amount delivered by each machine will be indicated by the pointer and dial plate thereon, which amount 100 may be more or less than or equal to the amount delivered by any other machine in the group, and the proportions may be varied as desired from time to time by adjusting the feed regulating device with which each 105 machine is provided. The several machines being set in motion, the material discharged into the conveyor-trough in the desired proportions will be thoroughly commingled 110 therein and discharged into a suitable receiver at the end of the conveyor.

Having thus described my invention, what I claim as new and desire to secure by Letters Patent of the United States is:

1. A machine of the character described 115 comprising a casing having an intermediate partition and a feed hopper at one side of said partition and a delivery chamber at the other side thereof and having a discharge opening in its bottom within said delivery chamber, a vertical shaft having its bearings within said delivery chamber in vertical alignment centrally of said bottom, a feed wheel on said shaft having a centrally disposed hub-like portion with spaced conveyor arms projecting outwardly therefrom into close proximity to cylindrical walls of the casing, and a feed regulating device consisting of an oscillatory plate underlying 120 said feed wheel between it and said bottom, 125 130

and means for adjusting said plate so as to vary the size of said discharge opening.

2. In a machine of the character described, a casing having an intermediate partition arranged to provide a feed hopper at one side and a delivery chamber at the other side of said partition, a feed wheel revolvably mounted under the bottom of the casing and having a series of conveyor arms projecting laterally therefrom into close proximity to curved walls of the casing on opposite sides of said partition, a bottom plate underlying said feed wheel and having a discharge opening therein within said delivery chamber, and adjustable means for enlarging or decreasing the size of said opening.

3. In a machine of the character described, a casing having an intermediate partition arranged to provide a feed hopper at one side and a delivery chamber at the other side of said partition, a feed wheel revolvably mounted under the bottom of the casing and having a series of conveyor arms projecting laterally therefrom into close proximity to curved walls of the casing on opposite sides of said partition, a bottom plate underlying said feed wheel and having a discharge opening therein within said delivery chamber, and adjustable means for enlarging or decreasing the size of said opening, together with means operable by said adjusting means for indicating the amount of material discharged when said opening is enlarged or decreased in size.

4. In a machine of the character described, a casing having front and rear portions and an intermediate partition constructed and secured together so as to form a feed hopper at one side of said partition and a delivery chamber at the other side thereof and a substantially cylindrical lower portion surrounding a circular bottom; said bottom having a discharge opening therein within said delivery chamber, a vertical shaft having its bearings within said delivery chamber in vertical alinement centrally of said bottom, a feed wheel on said shaft having a centrally disposed hub-like portion with spaced conveyor arms projecting therefrom outwardly into close proximity to said cylindrical portion of said casing, and a feed regulating device consisting of an oscillatory plate underlying said feed wheel between it and said bottom, and means for adjusting said plate so as to vary the size of said discharge opening.

5. A machine of the character described, comprising a divided casing having front and rear portions and an intermediate partition constructed and secured together so as to form a feed hopper at one side of said partition and a delivery chamber at the other side thereof and a cylindrical lower portion encircling a circular bottom; said

bottom having a discharge opening therein within said delivery chamber, a vertical shaft having its bearings within said delivery chamber, a feed wheel on said shaft having a centrally disposed hub-like portion with spaced conveyor arms extending outwardly therefrom into close proximity to said cylindrical portion of the casing; said arms being adapted to gather and push the material in the direction of movement, and means for varying the size of said discharge opening.

6. In a percentage feeding machine having means for collecting and discharging grain or granulated material in predetermined proportions for admixture with other grain coming from another machine or machines in a group, means for conducting the discharged material inwardly into a relatively fixed spout or conduit or outwardly into a receptacle at one side of the machine, when desired to measure or weigh the material to ascertain whether the machine is discharging in the desired proportion; the latter means comprising a chute consisting of depending inwardly inclined members spaced apart and hinged at their upper ends on opposite sides of the discharge port, and means for normally holding said members in an inwardly inclined position and for throwing them into an outwardly inclined position and sustaining them in the latter position or restoring them to normal position, as desired.

7. In a percentage feeding machine having means for collecting and discharging grain or granulated material in predetermined proportions for admixture with other grain coming from another machine or machines in a group, means for conducting the discharged material inwardly into a relatively fixed spout or conduit or outwardly into a receptacle at one side of the machine, when desired to measure or weigh the material to ascertain whether the machine is discharging in the desired proportion; the latter means comprising a chute consisting of depending inwardly inclined metal plates each having marginal flanges turned toward the other plate; said plates being spaced apart and hinged at their upper ends on opposite sides of the discharge port, and means for normally holding said plates in an inwardly inclined position and for throwing them into an outwardly inclined position and sustaining them in the latter position or restoring them to normal position, as desired.

8. A machine of the character described, comprising a casing having front and rear portions and an intermediate partition constructed and secured together so as to provide a feed hopper at one side of said partition and a delivery chamber at the other side thereof, said front part having a sub-

stantially semi-circular base portion and a rearwardly inclined upper part having an opening therein and a cover therefor; said partition having a centrally disposed substantially semi-circular portion spaced from the rear inner wall of said rear part; the latter being of approximately U-shaped form and diminishing in size toward its lower end which terminates in substantially semi-circular form concentric with said centrally disposed part of said partition, a feed wheel within said casing having a centrally disposed hub-like portion and spaced outwardly extending conveyor arms exposed on both sides of said partition, and a feed regulating device consisting of a circular plate underlying said feed wheel and having an opening therein underlying said conveyor blades within said discharge chamber and overlying a discharge port in the hopper bottom, and means for adjusting said plate to vary the size of said discharge opening.

9. In combination, a group of machines for feeding grain or granular materials simultaneously in predetermined proportions, each machine having a feed wheel revolubly mounted in the lower part of a casing having an intermediate partition to form a feed hopper at one side and a discharge chamber and housing for the feed wheel shaft and driving gearing therefor at the other side of said partition; said feed wheel being secured on a vertical shaft geared to a horizontal shaft having its bearings in said casing, means for connecting said shaft with a main driving shaft for imparting simultaneous rotary motion to the feed wheels of the group, a mixing device into which the materials fed by said group are conducted, means on each machine for increasing or decreasing the amount or proportion it may feed independently of other machines in the group, and means operable conjointly with the last named means on each machine for indicating the amount each machine may feed in a given period of time.

10. In combination, a plurality of machines for feeding grain or other material simultaneously in predetermined proportions, each machine having a feed wheel secured on a vertical shaft housed in a casing having an intermediate partition arranged to provide a feed hopper at one side and a delivery chamber at the other side of said partition; each of said machines being provided with independently operable means for increasing or decreasing the amount or proportion of material it may feed in a given period of time and having its feed wheel operatively connected with a main driving shaft for imparting rotary movement thereto, and means on each machine connected with and operated by the independently operable means thereon for indicating the

amount or proportion of material it may feed.

11. A machine for feeding grain or granular material in predetermined quantities, comprising a casing of cylindrical form at the lower end thereof and having a partition therein to form a feed hopper at one side and a housing for a feed wheel and its driving mechanism at the other side of said partition, and also having a discharge port in its bottom at the side thereof opposite said feed hopper, a feed wheel fixed on a vertical shaft having its bearings in said casing at the side of said partition opposite said hopper, said feed wheel having radially projecting conveyor arms exposed in a semi-cylindrical space around the hopper bottom and said discharge port arranged at the opposite peripheral portion of the feed wheel underlying the path of movement of said conveyor arms, means for increasing and decreasing the size of said port so as to increase or decrease the amount of material allowed to pass therethrough as desired, and a vertically adjustable gate or cut-off arranged over the conveyor arms at the point where the latter enter the discharge chamber.

12. A machine for feeding grain or granular material in predetermined quantities, comprising a casing constructed to form a feed hopper at one side and at the other side a housing for a feed wheel and its driving mechanism together with a feed wheel revolubly mounted and housed in said casing and separated from said hopper; said feed wheel having conveyor arms extending from a centrally disposed hub-like portion thereof to a cylindric wall of the casing and curved in the direction of rotation so as to push material toward the discharge port and deliver the same successively in equal proportions; said casing having a discharge port of arcuate form in its bottom at the side thereof opposite said hopper, an oscillatory plate resting on said bottom having an arcuate opening therein adapted to register with the discharge port in said bottom, means for adjusting said plate so as to increase or decrease the size of said discharge port, and means operable by said adjusting means for indicating variations in the amount of material discharged at each revolution of the feed wheel.

13. In combination, a casing constructed in separable parts together forming a feed hopper at one side of a centrally disposed partition and a discharge chamber and housing for a feed wheel at the other side of said partition, a feed wheel with its driving shaft and gearing housed in said discharge chamber and having curved conveyor arms projecting from a centrally disposed hub-like portion into close proximity to the inner wall of the casing, and an adjustable gate or cut-off on said partition at the point

where said conveyor arms pass into said discharge chamber.

14. In combination, a feed hopper, a feed wheel arranged to discharge material in pre-determined proportions through a port in the hopper bottom, a feed regulating device including an oscillatory plate for varying the size of said port, means for indicating variations in the amount of material discharged including a rotary pointer, and means for imparting an oscillatory move-

ment to said plate and simultaneously rotating said pointer; the latter means comprising a rod rotatably mounted on the machine frame and having a worm gear thereon engaging a segment gear on said oscillatory plate and also a worm gear engaging a gear wheel on the shaft of said rotary pointer. 15

In testimony whereof I affix my signature.

SIMON SNYDER.
